(57) **CLAIM**

The ornamental design for a retail display rack, as shown and described.

DESCRIPTION

FIG. 1 is a front, left perspective view of a retail display rack according to an embodiment;
FIG. 2 is a front, right perspective view of the retail display rack of FIG. 1;
FIG. 3 is a front elevation view of the retail display rack of FIG. 1;
FIG. 4 is a left side elevation view of the retail display rack of FIG. 1;
FIG. 5 is a right side elevation view of the retail display rack of FIG. 1;
FIG. 6 is a top plan view of the retail display rack of FIG. 1;
FIG. 7 is a bottom view of the retail display rack of FIG. 1;
FIG. 8 is a rear elevation view of the retail display rack of FIG. 1;
FIG. 9 is a front, left perspective view of a retail display rack according to another embodiment;
FIG. 10 is a front, right perspective view of the retail display rack of FIG. 9;
FIG. 11 is a front elevation view of the retail display rack of FIG. 9;
FIG. 12 is a left side elevation view of the retail display rack of FIG. 9;
FIG. 13 is a right side elevation view of the retail display rack of FIG. 9;
FIG. 14 is a top plan view of the retail display rack of FIG. 9;
FIG. 15 is a bottom view of the retail display rack of FIG. 9; and,

(Continued)

FIG. 16 is a rear elevation view of the retail display rack of FIG. 9.

The broken lines are for illustrative purposes only and form no part of the claimed design.

1 Claim, 12 Drawing Sheets
